DOLL HEAD STRUCTURE

Filed Nov. 15, 1927

INVENTOR.
Samuel Marcus

George H. French
ATTORNEY

UNITED STATES PATENT OFFICE

SAMUEL MARCUS, OF BROOKLYN, NEW YORK, ASSIGNOR TO MARKON MANUFACTURING CO., INC., OF NEW YORK, N. Y., A CORPORATION OF NEW YORK

DOLL-HEAD STRUCTURE

Application filed November 15, 1927. Serial No. 233,365.

This invention relates to an improvement in doll head structure, and a particular object of the invention is to provide such heads with portions which are of a different material or consistency from the material of the head said portions being located and adapted for the attachment of parts or devices which are formed separately from the head but which must be attached to the head in the completed doll structure, such for instance as eye sets and the like.

A more specific object is to provide a doll head molded of any appropriate material but containing inserts, or sections, of a special kind of material adapted to receive and support the eye sets or other devices, said inserts or sections being of course disposed in appropriate localities as may be necessary to serve their intended purpose.

In the manufacture of doll heads as heretofore practiced it has been customary to attach eye sets therein by means of pronged parts comprised in the sets and driven into the material of the head. The material from which doll heads are manufactured however has not always provided a proper anchor for the prongs of the eye set, being sometimes too hard, and sometimes too soft, etc., in the particular locality where the prongs engage, and it is therefore a specific object of the present invention to provide inserts, preferably baked into the head at the time of molding and baking the head so that said inserts will constitute substantially integral parts of the head and the inserts being of course of such material as to provide efficient and reliable anchorage for the prongs of the eye set.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claim.

In the accompanying drawings which are to be taken as a part of this specification, and in which I have shown merely a preferred form of embodiment of the invention:—

Fig. 1 is a vertical sectional view through the front wall of a doll head showing an insert comprised therein in accordance with this invention.

Fig. 2 is a fragmentary interior view of 55 the head shown in Fig. 1.

Figs. 3 and 4 are views similar to Fig. 2 but illustrating modified forms of the inserts, and

Fig. 5 is a horizontal sectional view 60 through a doll head showing still another form of insert.

Referring to the drawings for describing the exemplary structures illustrated therein, the reference character L indicates a doll head having the usual eye openings as 1 and 2 through its front wall and having opposite cheek portions as 3 and 4.

In the structures Figs. 1 to 4 the inserts G shown therein are arranged for attachment 70 of eye sets which include pronged attaching parts disposed between the two eyeballs, said eye sets being of the general type as disclosed in the pending application of Samuel Marcus, Serial No. 163,610. In this instance therefore the inserts G are embodied in the head 75 in the space between the two eye openings.

In the structure Fig. 5 the inserts G are arranged for attachment of eye sets which include pronged attaching parts disposed for 80 engaging the cheek portions of the head, said eye sets being of the general type as disclosed in the patent of Alexander Konoff, No. 1,621,072. In this instance therefore the inserts G are embodied in the cheek portions 85 of the head.

It will be understood therefore that the inserts G may be of any form and disposition as may be required according to the type of eye set or other device which is to be fastened 90 in position by means thereof.

In all instances the inserts are intended to be of a suitable material which may be uniformly reliable as an anchorage for receiving the prongs or other fastening devices of the 95 eye sets. Ordinary soft wood is suitable in many instances, although obviously any other appropriate material may be used.

In the structure Figs. 1 and 2 the insert consists of a body portion as 5 having upper 100

and lower lugs as 6 and 7 projecting rearwardly therefrom arranged to define a space as 8 between them within which the attaching member or carrier as H of the eye set may be received substantially in the manner as illustrated by the dotted lines in Fig. 1, it being noted that in this instance the body portion 5 is depressed wholly below the surrounding surface of the doll head so that opposite side wall portions as 9 and 10 of the material of the head occur between the lugs 6 and 7, thereby defining a definite pocket within which the carrier H may be received, the lugs 6 and 7 being adapted to receive the prongs as 11 and 12 of the carrier while the walls 9 and 10 insure correct positioning of the carrier between the lugs and centrally between the two eye openings of the head.

In the structure Fig. 3 the insert is the same as in Figs. 1 and 2 except that in this instance the insert is made to include side wall parts as 13 and 14 which furnish side wall surfaces as 15 and 16 respectively serving the same purpose as the walls 9 and 10 of the previous structure.

The walls 13 and 14, being of the same material as the remainder of the insert may if desired be utilized for receiving prongs of the eye carrier in some cases.

In the modification Fig. 4 the structure is the same as described with reference to Fig. 3 except that in this instance the central opening as 17 provided in the insert, instead of being rectangular as in Fig. 3, is circular, thereby adapting the insert for receiving an eye carrier or attaching member of a different type such for instance as that disclosed in Figs. 9 to 12 of the pending application of Alexander Konoff, Serial No. 161,915, all parts of the annular interior wall surface as 18 of said insert being equally adapted to receive prongs or like attaching parts thrust thereinto.

In the modification Fig. 5 the inserts comprise simple blocks of appropriate size and shape molded one with each of the cheek portions of the head, said blocks as shown providing opposing faces as 19 and 20 which are parallel with each other and properly placed to receive the eye set carrier or attaching member H.

Any suitable means may be employed for insuring an intimate connection of the inserts with the material of the doll head as may be required but for the purpose of illustration the drawing shows in each instance a flaring inner flange portion as 21 upon the insert to accomplish this result. It will be understood however that any other appropriate means may be employed and that even if desired the inserts may be cemented in position.

As many changes could be made in this construction without departing from the scope of the invention as defined in the fol-

lowing claim, it is intended that all matter contained in the above description, or shown in the accompanying drawings, shall be interpreted as illustrative only and not in a limiting sense.

Having thus described my invention, what I claim as new and desire to secure by Letters Patent is:—

A molded doll head having an insert molded as a part thereof serving as anchoring means for a separate device, said insert having a flaring portion embedded within the material of the doll head to prevent its separation from the doll head, and said insert being of a different material from the material of the doll head adapting it to receive attaching prongs of said separate device thrust thereinto.

In testimony whereof I affix my signature.

SAMUEL MARCUS.
